W. C. COLEMAN

CENTRIFUGAL SEPARATOR

Filed Sept. 15, 1924

Fig. 1.

Patented Aug. 10, 1926.

UNITED STATES PATENT OFFICE.

WILLIAM C. COLEMAN, OF WICHITA, KANSAS.

CENTRIFUGAL SEPARATOR.

Application filed September 15, 1924. Serial No. 737,860.

This invention relates to centrifugal separators for separating precious metal from placer sand or ore pulp and among the objects of the invention is a provision of means for passing the material to be treated through one or more stages, preferably through a plurality of stages between the inlet and the outlet of the machine.

In one aspect of the invention, it is intended to provide a perforate inner liner for each stage spaced from the main wall of the stage, so that mercury may pass from a subjacent mercury chamber upwardly between the inner liner and the wall of its stage when the device is subjected to centrifugal action to permit the mercury to repose in the perforations of the inner liner slightly within the inner ends of the perforations so that a plurality of mercury containing cups will be provided to extract the precious metal from the ore. I desire that the mercury lie slightly within the perforations so that the inner liner will have the effect of a riffle preventing scouring of the mercury and causing sufficient agitation of the ore pulp so that all of the sand will be subjected to the action of the mercury, the riffle being effective in preventing stratification of the ore pulp within the machine.

I have also found that with such a device amalgamator plates may be used to advantage, so I have provided cylindrical amalgamator plates within the machine which may be used with or without the inner liners, but I prefer to combine them with the inner liners as I believe that the best results can be obtained by the combination of the two.

The multiple staging provides a relatively long period of activity of the mercury upon the ore passing through the machine so I prefer a multi-stage machine in preference to a single stage machine, and the mercury traps or chambers are provided so that the mercury may gravitate thereinto when the machine is coming to a state of rest and be ready to be collected for the purposes of separating the contained gold, the traps also affording a convenient means for placing the mercury in proper position to insure its proper disposition when the machine is started up.

Other more or less important advantages will appear as the nature of the invention is better understood by reference to the fol-

lowing description in connection with the accompanying drawings, in which

Fig. 1 is a vertical, longitudinal, sectional view through a separator constructed in accordance with my invention.

Fig. 2 is an enlarged fragmentary sectional view showing part of the casing and the liner, and illustrating the mercury line when the device is operating.

The invention is illustrated as consisting of a cylindrical stator having a rotor therein divided into a plurality of concentric stages. The number of stages, however in so far as the generic adaptation of my invention is concerned is unimportant although specifically the construction shown is the one recommended.

The rotor or casing 1 is in the form of an open ended cylinder having at its upper end a peripheral outwardly disposed flange 2 to receive the flange 3 of a cover 4 having a threaded collar 5 into the threaded opening 6 of which may be secured a conduit or pipe for conveying the placer sand or ore pulp into the machine. In order to evenly dispose the incoming material about the machine, I provide a distributor disk 7 concentric with the rotor 1 and fast to the cover 4 by bolts 8. Secured to the constricted bottom portion 9 of the rotor 1 is a cylindrical wall 10 spaced from the inner face of the portion 9 and having an upstanding truncated conical end 11 provided with a central opening 12 which is the outlet opening for the machine. The wall 10 is fastened to the bottom 9 by bolts 13 which pass through the flange 14 of a cylindrical inner lining 15 spaced from the wall 10 provided with perforations 16 to receive mercury from the mercury chamber 17 formed by grooving the lower portion of the wall or offsetting it so that a chamber will be formed.

The cylindrical wall 15 extends to the base of the truncated portion 11 and it is of course concentric with the outer rotor 1. The outer rotor is provided with a perforate inner liner 18 supported upon the seat 19 by shallow feet or projections 20 so that mercury from the sump or chamber 21 formed by the space between the walls 9 and 10 can pass up through the space between the inner liner 18 and the wall of the rotor 1 and partially fill the perforations 22 of the inner liner as shown.

The cylindrical inner liner has a truncated conical bottom 23 provided with radial plates 24, the bottom being provided with a central opening to receive a threaded tube 5 with a flared bottom 26 below the outlet opening 12. Within the imperforate portion 27 of the inner liner 18 is a cylindrical partition consisting of a stepped up cylindrical member comprising the vertical walls 10 28, 29 and 30 connected by the horizontal webs 31 and 32, the top edge of the cylindrical wall 30 being closed by an end wall 33, the cylindrical stepped up structure having walls of progressively decreasing diameters which rest upon the seat 34 within the inner liner 18.

The outer wall 35 of the intermediate stage 20 36 is fastened to the web 31 by bolts 37 and it extends beyond the inner liner 18 which is clamped in place by the shoulder 38. The outer wall 35 of the intermediate stage is sufficiently spaced from the inner liner 18 to provide the space for the outer stage and it carries a cylindrical amalgamator plate 25 39. On its inner face there is an inner liner 40 generically like the inner liner 18 but it has an inturned lower edge 41 which is fastened to the web 32 by bolts 42. The space between the cylindrical wall 29 and the lower portion of the outer wall 35 of the intermediate stage provides a mercury chamber or trap 43 in which mercury will be received to spin up the space between the inner liner 40 and the wall 35 when the device 30 35 is rotated.

Resting upon the set screws 44 passing through the web 32 and the member 40 is a groove shaped lower end 45 of the inner wall for the first stage. It is cylindrical 40 and it constitutes the inner wall for the intermediate stage being provided with a cylindrical amalgamator plate 46 so that the cylindrical space 36 is formed for the intermediate stage similar to the manner in which the space 47 is formed for the outer sleeve.

The free end 48 of the member 45 carries a perforate inner liner 49 similar to the inner liners 18 and 40 having the same kind 50 of perforations and being spaced from the wall 46 of the wall of the first stage so that the mercury may move up from the mercury trap 50 into the perforations in the inner liner 49. Breather pipes 51 and 52 may be provided for the mercury chambers 43 and 55 50. Additional breather pipes may be provided wherever advantageous. Attention is called to the fact that the wall of the inner stage abuts against the cover 4, this being possible by adjusting the screws 44.

The machine may be rotated at a relatively high speed by any suitable means, for example by a pulley on the pipe (not shown) which is connected to the threaded portion 6 of the collar 5. When the device 60 65

is rotating and sand or ore pulp is fed in through the opening in the collar 5, it will be distributed in radial stream lines by the distributor 7 so that it first comes into contact with the mercury in the perforations of the inner liner 49 to be acted upon by the mercury. It gravitates through the space between the wall 30 and the inner wall of the member 45 and since the bottom of the member 45 is spaced from the inturned end 41 of the member 40, the sand and pulp will pass from the first inner concentric stage to the intermediate concentric stage 36 being subjected to the action of the mercury in the inner liner 40 and to the amalgamator plate 46. It will then pass over to the outer stage where it will be subjected to the action of the amalgamator plate 39 and the mercury in the inner liner 18. During its passage through the outer stage, it will 80 85 90 95 100 105 110 115 120 125 130 135 140 145 150 155 160 165 170 175 180 185 190 195 200 205 210 215 220 225 230 235 240 245 250 255 260 265 tor from the sump so that the pulp or sand cannot enter the sump which is now devoid of mercury, due to the fact that the centrifugal force has moved the mercury up into the cups.

5 What I claim and desire to secure by Letters-Patent is:—

1. A centrifugal separator having a mercury stage and a perforate inner liner for 10 the stage provided with mercury cups, there being a mercury passageway between the inner liner and the wall of the stage adapted to

15 deliver mercury to the cups and a mercury chamber at the bottom of the stage communicating with the passageway.

2. In a centrifugal separator, a rotor having an inlet and an outlet, a perforate inner liner within the rotor being spaced at least in part from the wall of the rotor and 20 a mercury chamber in the bottom of the rotor communicable with the perforations through the spacing between the inner liner and the rotor.

25 3. In a centrifugal separator, a rotor having an inlet and an outlet, a perforate inner liner within the rotor being spaced at least in part from the wall of the rotor and a mercury chamber communicable with the perforations through the spacing between 30 the inner liner and the rotor.

4. In a centrifugal separator, a rotor having a plurality of concentric stages, each provided with mercury cells along its wall, each stage having a mercury chamber for supplying mercury to the mercury cells, and passageways between the stages for permitting material passed through the machine to by-pass the mercury chambers in passing from one stage to the other.

40 5. In a centrifugal separator, a rotor having a plurality of concentric stages, each provided with mercury cells along its wall, each stage having a mercury chamber for supplying mercury to the mercury cells, and 45 passageways between the stages for permitting material passed through the machine to by-pass the mercury chambers in passing from one stage to the other, the mercury chambers communicating with the stages 50 through the mercury cells only.

6. A centrifugal separator comprising a plurality of concentric stages, perforated inner liners in the stages, separate mercury

chambers for supplying mercury to the perforations in the inner liners and passageways communicating the stages one with the other, the mercury chambers being sealed off from the passageways.

7. A centrifugal separator comprising a plurality of concentric stages formed by cylindrical inner and outer walls in spaced relation, mercury cups on the inner walls of the concentric stages and amalgamator plates on the outer walls of the inner stages.

8. A centrifugal separator comprising a plurality of concentric stages in communication, means for supplying mercury to the inner walls of the respective stages during rotation of the amalgamator, a bottom member for the amalgamator comprising an internal conical wall provided with an outlet opening and mercury cups on the inner wall below the outlet opening.

9. A centrifugal separator comprising a plurality of concentric stages in communication, means for supplying mercury to the inner walls of the respective stages during rotation of the amalgamator, a bottom member for the amalgamator comprising an internal conical wall provided with an outlet opening and mercury cups on the inner wall below the outlet opening, an amalgamator plate carried by the conical wall adjacent to the mercury cups.

10. In a centrifugal separator, a rotor having an inlet and an outlet, a perforate inner liner within the rotor being spaced at least in part from the wall of the rotor and a mercury chamber communicable with the perforations through the spacing between the inner liner and the rotor, the communicable ways being located so that they remain sealed from the interior of the rotor with mercury while the rotor is revolving.

11. In a centrifugal separator, a rotor having an inlet and an outlet, a perforate inner liner within the rotor being spaced at least in part from the wall of the rotor and a mercury chamber communicable with the perforations through the spacing between the inner liner and the rotor, the communicable ways being sealed from the interior of the rotor while the rotor is revolving.

In testimony whereof I affix my signature.

WILLIAM C. COLEMAN.
